To all whom it may concern:

Be it known that I, Abraham Greenspan, a citizen of the United States of America, residing in Manhattan, county of New York, and State of New York, have invented a new, original, and ornamental Design for a Dress, of which the following is a specification, reference being had to the accompanying drawing, forming part thereof, wherein,

The lines extending down the sides of the neckline and around the pockets, represent cording.

The vari-shaped figures between the cordings at the neckline, represent a paisley material.

I claim:

The ornamental design for a dress, substantially as shown, and described.
